UNITED STATES PATENT OFFICE.

GEORGE FRANCIS HOGAN, OF CHICAGO, ILLINOIS.

ANKLE PROTECTOR.

Application filed November 18, 1925. Serial No. 69,831.

This invention relates to protectors intended more particularly to prevent the soiling of ladies' silk hosiery.

Since the commencement of the present 5 vogue of silk hosiery in delicate colors and shades which are worn usually with low shoes or slippers the damage to such articles which results from splashing with mud and dirty water has been a matter of considerable 10 comment. Hosiery is frequently ruined after a single wearing during rainy weather because it is practically impossible to remove the spots and stains, and the hosiery is often so disfigured that it is no longer 15 available for use.

It is the object of the present invention to provide a simple and inexpensive protector of small bulk which can be carried handily and applied quickly for the purpose of protecting hosiery.

Further objects and advantages of the invention will be apparent as it is better understood by reference to the following specification and accompanying drawing, in 25 which

Fig. 1 is a plan view of the protector; and

Fig. 2 is a view in perspective illustrating the application thereof.

The protector may be made of any light 30 fabric. Preferably a strong tough non-absorbent paper is utilized since this material is cheap, the protectors can be stamped therefrom with a die and can be discarded after a single use because they are quite inexpensive. In order that the protectors may 35 fit the ankle snugly I prefer to employ a paper having a crepe finish which permits it to crinkle when it is secured in place by the fastening means. To facilitate fastening in 40 a simple manner it is possible to use a cord or string with suitable means to secure the ends thereof and to bind and hold the protector in its proper position. The cord or string should be secured to one end of the 45 protector and the fasteners should be so arranged that the cord or string can be passed under and across the instep after the protector has been wrapped about the ankle. This arrangement prevents the protector 50 from riding upwardly and holds it snugly about the ankle, thus avoiding ineffectiveness and an unsightly appearance. When constructed and applied in the manner described the protector affords a neat and inconspicuous wrapper for the ankle. It is substantially non-absorbent and will protect the

hosiery from becoming wet and from being splashed with muddy water. The nature of the protector is such that it can be carried easily in a hand bag and applied when 60 needed. It is particularly effective under conditions which do not warrant the wearing of overshoes or other cumbersome forms of protection for the ankles.

Referring to the drawing, Fig. 1 illustrates a protector designed for use upon the right ankle. The protector for the left ankle is identical in form but is reversed with respect to the tabs and fastening means. The protector comprises a body portion 5 with a depending flap 6 which is adapted to fit over the instep and tabs 7 and 8, the former being adapted to slip beneath the latter when the protector is disposed about the ankle. A string or cord 9 is secured to 75 the tab 8 and to a fastener 10 consisting of a paper disc riveted to the tab. This fastener is of the type commonly employed for securing envelopes. Two similar fasteners 11 and 12 are secured to the body 5 of the protector in the medial line thereof, these fasteners being spaced apart so as to be approximately at the sides of the ankle.

The protector is applied as indicated in Fig. 2 of the drawing which shows the application thereof to the left ankle. The protector is wrapped about the ankle with the tab 8 carrying the fastener 10 on the outside and the string or cord 9 is drawn about the fastener 12 and is passed thence beneath the 90 instep and about the fastener 11. The cord or string is then passed over the instep, causing the protector to be gathered in to ensure a neat appearance and it is finally secured again to the fastener 12. The protector is 95 thus firmly bound to the ankle and held closely to the shoe. By passing the cord beneath the instep the protector is prevented from shifting upwardly. It affords, therefore, a neat and satisfactory protection for 100 the ankles and it can be removed quickly and discarded when it is no longer needed.

While I prefer to make the protector of paper as indicated, it is obvious that various kinds of fabrics may be substituted therefor. For ordinary purposes a dense non-absorbent paper provides all of the necessary protection. The paper can be treated, however, with various materials to decrease its absorbent power and it can be coated and 110 colored to suit the requirements. If other fabrics are employed they may be colored as

desired and may be rubberized or otherwise rendered non-absorbent or water-proof.

Various changes may be made in the details of the form and arrangement of the protector without departing from the invention or sacrificing any of the advantages thereof.

I claim:—

1. An ankle protector comprising a body portion of paper creped to be laterally extensible, a flap to cover the instep of the wearer and clasping means adapted to pass beneath and over the instep to secure the protector in place.

2. An ankle protector comprising a body portion, a flap to cover the instep of the wearer and a fastening adapted to pass beneath and over the instep to secure the protector in place, including a cord and means arranged to be disposed at opposite sides of the ankle to secure the cord.

3. An ankle protector comprising a body portion, a flap to cover the instep of the wearer, three fasteners arranged in spaced relation in approximately the horizontal medial line of the body portion and a cord secured to one of the fasteners and adapted to be secured successively to the others.

4. An ankle protector comprising a body portion of paper creped to be laterally extensible and means for binding the protector about the ankle of the wearer.

5. An ankle protector comprising a body portion of paper creped to be laterally extensible and means for binding the protector about the ankle of the wearer, the binding means being adapted also to pass beneath the instep.

6. An ankle protector comprising a body portion of paper creped to be laterally extensible having a flap to cover the instep of the wearer and a fastening adapted to pass beneath and over the instep to secure the protector in place.

7. An ankle protector comprising a body portion of paper having a flap to cover the instep of the wearer and a fastening adapted

to pass beneath and over the instep to secure the protector in place, including a cord and means arranged to be disposed at opposite sides of the ankle to secure the cord.

8. An ankle protector comprising a body portion of paper creped to be laterally extensible, a flap to cover the instep of the wearer and tabs at the ends to overlap when the protector is in place, means for securing the protector in position and means to prevent the protector from shifting upwardly from the instep.

9. An ankle protector comprising a body portion, a flap to cover the instep of the wearer and tabs at the ends to overlap when the protector is in place and means for securing the protector in position and to prevent it from shifting upwardly from the instep, including a cord and fasteners arranged to be disposed at opposite sides of the ankle.

10. An ankle protector comprising a body portion of paper creped to be laterally extensible, a flap to cover the instep of the wearer and tabs at the ends to overlap when the protector is in place and means to bind the protector about the ankle.

11. An ankle protector comprising a body portion of paper extensible laterally about the ankle and means for binding the protector about the ankle of the wearer.

12. An ankle protector comprising a body portion of extensible paper, a flap to cover the instep of the wearer and fastening means adapted to pass beneath and over the instep to secure the protector in place.

13. An ankle protector comprising a body portion of extensible paper, having a flap to cover the instep of the wearer and a fastening adapted to pass beneath and over the instep to secure the protector in place.

14. An ankle protector comprising a body portion of extensible paper, a flap to cover the instep of the wearer and tabs at the ends to overlap when the protector is in place and means to bind the protector about the ankle.

In testimony whereof I affix my signature.

GEORGE FRANCIS HOGAN.
